US0D1102412S

(12) **United States Design Patent** (10) **Patent No.:** **US D1,102,412 S**
(45) **Date of Patent:** **** Nov. 18, 2025**

(54) **EMBEDDED MULTIMEDIA TERMINAL ADAPTER**

(71) Applicant: **Charter Communications Operating, LLC**, St. Louis, MO (US)

(72) Inventors: **Ethan Miller**, Parker, CO (US); **Chelsea Young**, Englewood, CO (US); **Ian Ruppert**, Denver, CO (US); **Daniel Allen**, Denver, CO (US); **Samuel Ach**, Aurora, CO (US); **Colin Downer-Carlson**, St. Louis, MO (US)

(73) Assignee: **Charter Communications Operating, LLC**, St. Louis, MO (US)

(**) Term: **15 Years**

(21) Appl. No.: **29/905,045**

(22) Filed: **Oct. 16, 2023**

(51) LOC (15) Cl. **14-03**

(52) U.S. Cl.

USPC **D14/240**

(58) **Field of Classification Search**

USPC D14/349-352, 358, 432, 433, 439, 137, D14/140, 155, 230, 240, 242

CPC H01Q 1/2291; H01Q 1/246; H04W 88/08

CLAIM

The ornamental design for an embedded multimedia terminal adapter as shown and described.

DESCRIPTION

FIG. 1 is a front-top perspective view of the embedded multimedia terminal adapter.

FIG. 2 is a back-bottom perspective view of the embedded multimedia terminal adapter.

FIG. 3 is a front side view of the embedded multimedia terminal adapter.

FIG. 4 is a back side view of the embedded multimedia terminal adapter.

FIG. 5 is a right view of the embedded multimedia terminal adapter.

FIG. 6 is a left view of the embedded multimedia terminal adapter.

FIG. 7 is a top view of the embedded multimedia terminal adapter; and,

FIG. 8 is a bottom view of the embedded multimedia terminal adapter.

The broken lines shown in FIGS. 1-8 represent portions of the embedded multimedia terminal adapter that form no part of the claim.

1 Claim, 8 Drawing Sheets

US D1,102,412 S
